G. M. DIMMOCK.

SCHOOL APPARATUS TO ILLUSTRATE THE ROTATION OF THE EARTH BY
MEANS OF THE VIBRATIONS OF A PENDULUM.

No. 9,839.

Patented July 12, 1853.

UNITED STATES PATENT OFFICE.

GEO. M. DIMMOCK, OF SPRINGFIELD, MASSACHUSETTS.

APPARATUS FOR ILLUSTRATING THE MOTION OF PENDULUMS UPON THE EARTH'S SURFACE.

Specification of Letters Patent No. 9,839, dated July 12, 1853.

To all whom it may concern:

Be it known that I, GEORGE M. DIMMOCK, of Springfield, in the county of Hampden, State of Massachusetts, have invented a new 5 and useful Improvement to Illustrate the Rotation of the Earth by Means of the Vibrations of a Pendulum on an Artificial Globe, which I call the "Foucaulator;" and I do hereby declare that the following is a 10 full, clear, and exact description of the construction and operation of the same; and I refer to the annexed drawings, making a part of this specification, in which—

Figure 1 is an elevation of the globe showing 15 the pendulum attachment in perspective; Fig. 2 is a section.

The same letters indicate like parts on both of the figures.

A, is a common artificial globe.

20 B, is the stand with a stem entering into the globe which supports it and upon which the globe revolves.

C, is the stand or tower upon which the pendulum is hung or suspended.

25 D, is the nut or thumb screw for moving and fastening the tower at any required latitude.

E, is the dial the center of which is on a 30 line between the top of the tower and the center of the globe with the principal points of the compass marked on it to show more plainly to the eye the independent movement of the pendulum. The arm that supports the dial extends under the thumb nut 35 to the tower and answers for a washer to the same.

F, is the band or strap which supports the tower and upon which the tower is moved from the pole to the Equator.

40 G, G, are two plugs driven firmly into the globe with the heads projecting, for firmly fastening the ends of the band on.

H is the crank for turning the globe which is fastened between the top plug head 45 and band. One screw secures both crank and band.

I, is a pendulum firmly secured in the point of the conical head of a bolt which 50 passes through the top of the tower and fastens with a thumb nut. I use a different pendulum for different latitudes, the pendulum rods I generally make of fine brass wire, rolling them between two smooth steel plates to give them evenness of elasticity so as to 55 form delicate springs not having a tendency

to bend one way more than another. For any latitude between the poles I bend or spring the pendulum rods to overcome the gravity of the earth so when at rest they will hang on the line from the point of suspension and the center of the globe, terminating in a ball directly over the center of the dial.

J, is the catch to hold the pendent terminus of the pendulums from over the dial 65 ready to release and set them to vibrating when the globe is revolving. This catch is attached to the tower by two points, one on the inside of the end of each prong entering two sockets, one on each side of the tower, 70 the prongs being bent together a little and the points sprung into the sockets so that it will rise and fall easy.

K is an elbow lever the fulcrum of which is attached to the globe near the bottom, the 75 long arm extending under the lower end of the strap.

L, is a circular plate firmly secured to the stand B and is cut out on the edge so that the short arm of the lever by resting against 80 the edge will rise slow and then fall, by turning the globe on the stand.

M, is a spring to bear on the lever.

N, is a narrow braid or string leading 85 from the catch J to the end of the long arm of the lever K, where it passes under a spring which holds it lightly so that it may be slipped either way.

The operation of this machine is as follows: Take a pendulum for any degree of 90 latitude and fasten it firmly to the top of the tower with the bolt and thumb nut; then with the thumb nut D, move the tower so that the pendulum ball will hang over the center of the dial; then turn the globe until the lever K falls to its lowest point on the plate L; then take hold of the string N, below the lever and pull down gently until the catch J, rests on the thumb nut D, then turn 95 the globe until the lever rises, then bend the pendulum toward the tower and raise the catch so that it will hold the pendulum by the ball; then turn the globe gently by the crank H and when the lever falls it pulls down the catch with the string and that sets 100 the pendulum to vibrating, and as the globe moves around, it illustrates the principle plainly to the eye, by the change of the vibrations of the pendulum relatively to the 105 degrees of the dial.

What I claim as my invention and desire to secure by Letters Patent, is—

1. The application to an artificial globe of one or more pendulums, the rods of which are formed of delicate springs so as to vibrate evenly, to all points of a dial, the plane of which is at right-angles to the pendulum when at rest.
2. I claim the bending or springing the pendulum rods, to counteract the gravity of the earth, so when at rest they will be straight and on the line from the point of

suspension, and the center of the globe; furthermore I claim anything substantially the same. I do not claim a ball suspended or strung on a string or thread and applied to an artificial globe, or applied in any manner whatever to illustrate the rotation of the earth by the vibrations of a pendulum.

GEORGE M. DIMMOCK.
